UNITED STATES PATENT OFFICE.

THOMAS J. JOHNSTON, OF SCHENECTADY, NEW YORK, ASSIGNOR TO THE GENERAL ELECTRIC COMPANY, OF NEW YORK.

PROTECTING GENERATORS IN TRANSMISSION PLANTS.

SPECIFICATION forming part of Letters Patent No. 678,185, dated July 9, 1901.

Application filed February 18, 1899. Serial No. 705,981. (No model.)

To all whom it may concern:

Be it known that I, THOMAS J. JOHNSTON, a citizen of the United States, residing at Schenectady, in the county of Schenectady, State of New York, have invented certain new and useful Improvements in Protecting Generators in Transmission Plants, (Case No. 1,110,) of which the following is a specification.

The present invention relates to the protection of generators, particularly of alternating-current transmission plants. It is in some respects applicable to any separately-excited machine; but its greatest utility will be found in the case named. Great difficulty arises in breaking the circuit in such plants because of the high voltage on the transmission-lines. Where the main circuit is itself broken, it is not unusual for the arc to hold across from one side to the other of the circuit-breaker, sometimes even destroying the devices which are intended to open the circuit or prevent the arc from spanning the contacts. I therefore provide a circuit-breaking apparatus in the field-magnet circuit of the generator with a current-measuring device operated from the line and acting upon the circuit-breaker, so that when the current rises to a determined maximum the field-magnet circuit of the generator is opened. For this purpose I prefer current-transformers in the main line, the tripping-coil of the circuit-breaker being in series with the transformer and having in circuit with it a regulable resistance by which the effect of the coil may be determined. Where the transmission-line supplies rotary converters, a difficulty arises which prevents ordinary circuit-breaking apparatus being efficacious—that is, when the circuit is opened the potential drops, but almost instantly the rotaries begin to feed back into the line a leading current which furnishes an excitation to the generator-armature, and the latter then feeds the line with current at a potential sufficient in many cases to span the gaps at the circuit-breaker, though not of so high a potential as that for which the plant is primarily designed. To provide against this, I not only open the field-circuit of the generator, so that there can be no inductive effect from the field, but I also pro-

vide an arrangement for opening the main circuit, operated by the same current-transformer before referred to. Where step-up transformers are used, I prefer to interpose the circuit-breaking arrangement, as well as 55 the current-transformer, in the primary line of the transformer; but where a high-potential generator is employed this of course becomes impossible and the apparatus would be operated directly from the transmission-line. Of course for the purposes of this invention either may be called with propriety the "main line."

In the accompanying drawings, Figure 1 is a diagram showing an embodiment of the invention in the form in which it is used with 60 a step-up transformer. Fig. 2 is an illustrative diagram.

A is the armature, indicated diagrammatically by the three collector-rings of a three-phase generator, supplying energy to the circuit, the leads of which are numbered 1 2 3. A step-up transformer T furnishes the required high potential to the transmission-line a b c. A series or current transformer T is 70 employed to furnish the desired energy for the circuit-breakers C D, the first of which is in the circuit of the field AF of the alternator (fed by the exciter E) and the second of which is in the low-potential side of the step-up transformer. The transformer T has coils t' t² in two of the lines of the three-phase system, acting upon a common secondary coil t³. In circuit with this secondary is the tripping-coil c of the circuit-breaker C. A regulable 75 resistance RC in series with it adjusts its effect to the value desired. Of course the resistance might be in multiple with the coil. A similar coil d acts upon the latch of the circuit-breaker D, and a similar resistance 80 RD adjusts its effect.

The operation of the apparatus is as follows: Assume, for instance, that a short circuit or other undue flow of current occurs between the lines a b. This would be reflected 85 back through the transformer T' to the coil t² of the transformer T, and a current above that at which the circuit-breakers are set to act would flow in the coils c d. The circuit-breaker C would open, killing the field AF of 90 95 100

the alternator. At the same time the circuit-breaker D would also open, opening the circuit between the transformer T' and the generator-armature.

5 In the three-phase system, which I have chosen as a convenient one for illustration of my invention, it is necessary to use only two of the coils t' t^2 in the current or series transformer. This arrangement is an effective safeguard against an overload between any two of the lines. It also enables me to adjust the circuit-breakers to the desired current-flow in any one of the lines. If three coils were used, there would be, as is well known, no effective magnetization of the transformer, while if the connections of one of the coils should be reversed, as is sometimes proposed, the effect in the transformer secondary would be twice that due to the current in any one of the lines, according to the well-known principles of alternating currents. The effect of the two coils is therefore a function of the current-flow in either of them. At the same time, as already pointed out, the desired indication of undue current in any of the three lines is furnished.

By referring to Fig. 2, which is a diagram illustrating, by means of the well-known parallelogram of forces, the currents in the lines, 30 the action will be better understood. Here the currents in the coils t' t^2 are indicated by lines bearing corresponding letters, while the third line t^4 is the resultant of the current-flow in the two coils and indicates the effective magnetization of the secondary by the two coils. It will be seen that where the currents are displaced one hundred and twenty degrees, as in a three-phase system, the resultant t^4 is of the same amplitude as either of the 40 currents t' t^2 .

I do not mean by this explanation to limit the invention to three-phase systems only, as it is manifest that it may be conveniently employed and will be of utility not only in 45 alternating-current systems of any number of phases, but under some circumstances with continuous-current machines.

What I claim as new, and desire to secure by Letters Patent of the United States, is—

1. In a polyphase system, the combination 50 of a series transformer having primary coils in more than one of the lines, and a common secondary for the coils, with a circuit-controlling device in the exciting-circuit of the generator, operated by the current in the secondary of the series transformer.

2. In a three-phase system, the combination 60 of a series transformer having primary coils in two of the lines, with a common secondary, and a circuit-breaker supplied with current from the secondary and arranged to open the exciting-circuit of the generator when the current reaches a determined value.

3. The combination with a series transformer in an alternating-current system, of a 65 circuit-breaker in the main line, and another circuit-breaker in the exciter-circuit, the two connected in multiple to the secondary of the transformer.

4. In a polyphase system, the combination 70 of a plurality of transformers connected with different mains, a secondary circuit supplied by the several transformers, and a circuit-breaker governing potential of the system, controlled by the secondary circuit. 75

5. In a polyphase system, the combination 80 of a series transformer having a single secondary and a plurality of primary coils in series in different lines of the system, with a circuit-breaker for opening all of the lines, 85 having its tripping-coil in series with the secondary of the transformer and an adjustable resistance, and a second circuit-breaker in the generator exciter-circuit, having its tripping-coil connected in series with the same 85 secondary and in multiple with the tripping-coil of the other circuit-breaker, and a second adjustable resistance in series with the coil.

In witness whereof I have hereunto set my hand this 16th day of February, 1899.

THOMAS J. JOHNSTON.
